Primary Examiner — Wan Laymon(57) **CLAIM**

The ornamental design for a measuring tool for dental, as shown and described.

DESCRIPTION

FIG. 1 is a perspective view of a measuring tool showing the new design for a measuring tool for dental.

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a magnified view of a portion of the measuring tool shown in FIG. 1, along lines A-A and B-B.

The broken lines shown in the figures represent portions of the measuring tool for dental that form no part of the claimed design.
